1 Claim

ABSTRACT OF THE DISCLOSURE

This invention relates to alkylamine and heterocyclic amine esters of 2-phenyl-cyclohexen-3-carboxylic acid as well as physiologically acceptable salts thereof. These new compounds have been found to have antispasmodic and antiulcer action. The invention also relates to the production of these compounds.

CROSS REFERENCE TO RELATED APPLICATION

This application is a divisional of my copending application Ser. No. 766,029, filed Oct. 2, 1968, now U.S. Pat. No. 3,699,109 granted on Oct. 17, 1972, for the "Tropyl Ester of 2-Phenyl-Cyclohexen-3-Carboxylate."

BACKGROUND OF THE INVENTION

This invention relates generally to alkylamine esters, and heterocyclic amine esters of 2-phenyl-cyclohexen-3-carboxylic acid, as well as to physiological acceptable salts thereof, which compounds exhibit antispasmodic and antiulcer action. The invention further relates to the production of these compounds as well as to the quaternization compounds of the basic esters with alkyl halides. Thus, the compounds can be utilized with respect to their antispasmodic activity associated with a normalizing action of the gastric and intestinal hyperkinesia, and antiulcer activity.

SUMMARY OF THE INVENTION

Generally speaking, the present invention provides compounds of the following general Formula 1:

wherein R=

—H; —CH₂—CH₂—N(C₂H₅)₂; —CH₂—CH₂—N(CH₃)₂;

2

Within the scope of this invention there are also included the salts of these basic esters with inorganic and organic acids (such as hydrochloric, sulphuric, citric, tartaric, and malonic acids), as well as the quaternization compounds of the above basic esters with inorganic alkyl esters (such as CH₃I; C₂H₅Br);

C₄H₉Br) of the type C_xH_yX, wherein C_xH_y is a linear or branched aliphatic chain having from 1 to 10 carbon atoms and X is a chlorine, bromine or iodine atom.

2-phenyl-cyclohexen-3-carboxylic acid (Formula I), wherein R=—H has been obtained by heating 2-phenyl-2-hydroxy-cyclohexen-3-carboxylic acid (Formula II below) in organic solvents, such as carbon tetrachloride, in the presence of catalytic amounts of mineral acids (such as sulphuric acid), according to the scheme:

50 The amino esters have been obtained by the following methods as shown in Scheme I;

(a) by treating the sodium or potassium salt of acid (I) with the corresponding amino-alkyl halide in alcohol medium (such as in isopropanol);

55 (b) by reacting the chloride of acid (I), being prepared in turn by heating said acid with SOCl₂ or by chlorination with PCl₅, with the desired amino-alcohol or its potassium salt;

60 (c) by transesterification reaction from ethyl-2-phenyl-cyclohexen-3-carboxylate with the selected amino-alcohol, in the presence of traces of alkaline ethylates.

(B)

(C)

wherein R' is the same as R excepted where R=—H.

The antispasmodic activity of the esters has been determined on segments of various isolated organs and it could be appreciated that the most tested products inhibit or prevent the contraction as due to several spasmodic agents both of hormonal and humoral essence and of a different essence; for some of the tested products, such as 2-phenyl-cyclohexen-tropyl carboxylate

this inhibiting or preventive activity is already apparent at concentrations of 1×10^{-7} to 1×10^{-8} g./ml. The pharmacological features and the collateral effects of the compounds are substantially superimposable to those of atropine, so that the products are particularly suitable for the therapy of spasms in the smooth musculature of the biliary, urogenital and digestive system tracts. Such curative use is useful with respect to atropine on account of the higher therapeutic ratio as provided by the compounds of this invention.

The antiulcer activity has been determined through many tests, such as histamine ulcer, contention ulcer, desamethazone ulcer and pylorus ligature ulcer. Some of these products proved to effectively inhibit ulcers from being arisen, whereby they can be considered as useful agents in the therapy of gastric and duodenal ulcers.

DESCRIPTION OF PREFERRED EMBODIMENTS

The following examples are given to further illustrate the present invention. The scope of the invention is not, however, meant to be limited to the specific details of the examples.

EXAMPLE 1

2-phenyl-cyclohexene-3-carboxylic acid (Formula I, wherein R=—H)

5 A mixture comprising 50 g. of 2-phenyl-2-hydroxy-cyclohexan-carboxylic acid, prepared in accordance with the method as described in literature, 2 ml. of concentrated sulphuric acid and 500 ml. of carbon tetrachloride is refluxed for 24 hours and thoroughly stirred.

10 The solvent is removed and the residue is treated with a 10% aqueous solution of sodium bicarbonate and after ether wash the alkaline solution is acidified with dilute hydrochloric acid. 30 g. of crystalline product melting at 76–80° C. are obtained (as crystallized from ligroin). The yield is 65% of the theoretical value.

15 Method (a).—2-phenyl - cyclohexene-3-carboxylate of 3-diethylamino-2,2-dimethyl-propyl:

25 5 g. (0.0248 mol) of 2-phenyl-cyclohexene-3-carboxylic acid, 20 cc. of isopropanol, and 0.97 g. (0.0248 mol) of potassium dissolved in 10 cc. methanol are introduced into a three-neck flask and 4.4 g. (0.0248 mol) 3-diethylamino-2,2-dimethyl-propyl chloride are added to the solution.

30 The reaction mixture is stirred and reflux heated for 3 hours, the precipitated potassium chloride is filtered and the solvent removed under vacuum.

35 The oily residue obtained is dissolved in ether, the ether solution is washed with 10% sodium hydroxide and then with water until the alkalinity is removed, then dried with anhydrous sodium sulphate and vacuum evaporated.

40 The yellow oily product thus obtained is purified by reduced pressure distillation, thereby obtaining 3 g. yellow oil B.P.0.2 mm. Hg 162–166° C.

Method (b).—Tropyl - 2 - phenyl - cyclohexen-3-carboxylate:

50 A mixture comprising 4.4 g. of tropine, 1.2 g. potassium and 40 ml. toluol is reflux heated under stirring until complete dissolving. To the toluene suspension obtained, a solution of 2-phenyl-cyclohexen-3-carboxylic acid chloride (Formula I, wherein R=H) (as prepared by treating 6.26 g. acid with 19 ml. thionyl chloride and then evaporating to dryness) in 30 ml. of toluol is added, and the mixture is reflux heated under stirring for 12 hours.

55 The solvent is vacuum evaporated, the residue is treated with dilute HCl, the acid solution is ether washed and then alkalinized and accurately extracted with ester.

60 After dehydration, the ether solution is evaporated, yielding a maroon dense oil, which is purified by fractional distillation at a reduced pressure, B.P.0.1 mm. Hg 168° C.

Method (c).—N - methyl - 3 - piperidine-2-phenyl-cyclohexen-3-carboxylate:

70 Into a 50 cc. Claisen flask, provided with a Liebig freezer, a vacuum junction and a collecting flask, there are introduced 5 g. (0.027 mol) ethyl-2-phenyl-cyclohexen-3-carboxylate, 5.4 g. (0.047 mol) 3-hydroxy-N-methyl-75 piperidine, 0.13 g. (0.0057 mol) sodium dissolved in the

required amount of ethyl alcohol and the mixture is heated at 120° C. and 80 mm. Hg for 2½ hours.

At completion of the heating a brick red oil is obtained and treated with 0.1 HCl. The hydrochloric solution is extracted with ether, alkalized with dilute sodium hydroxide, the precipitated product is extracted with ether and after drying with anhydrous sodium sulphate ether is evaporated.

The raw product thus obtained is purified by fractional distillation at a reduced pressure, yielding 2.35 g. of a 10 yellow fluid oil, B.P._{0.05} mm. Hg 154–155° C.

EXAMPLE 2

3-diethylamino-2,2-dimethyl-propyl-2-phenyl-cyclohexen-3-carboxylate methyl iodide

15

Into a flask, provided with a reflux freezer having a tube filled with CaCl_2 , there are introduced 0.8 g. 3-diethylamino-2,2-dimethyl-propyl-2-phenyl-cyclohexen-3-carboxylate, 0.4 g. methyl iodide and 3 cc. methanol. The mixture is heated for 7 days in an oil bath at 45° C. 20 Crystal separation not being obtained by cooling, the solvent is vacuum removed, thus obtaining a yellow resinous residue attaining a resinous appearance after ether washes; the compound thus obtained shows analytical features corresponding to the product expected. 25

The following compounds having the characteristics indicated were prepared in accordance with the above described methods:

3 - (N - morpholine) - 2,2 - dimethyl-propyl-2-phenyl-cyclohexene-3-carboxylate, obtainable by methods (a), 30 (b), (c): colourless dense oil, B.P._{0.15} mm. Hg 177–178° C.

2 - diethylamino - 1 - methylethyl-2-phenyl-cyclohexen-3-carboxylate, obtainable by methods (a), (b), (c): light yellow oil, B.P._{0.2} mm. Hg 140° C.

2 - dimethylaminoethyl - 2 - phenyl-cyclohexen-3-carboxylate, obtainable by methods (a), (b), (c): colourless fluid oil, B.P._{0.2} mm. Hg 130–132° C.

2 - (2' - diethylaminoethoxy) - ethyl-2-phenyl-cyclohexen-3-carboxylate, obtainable by methods (b), (c): 40 orange-yellow oil, B.P._{0.2} mm. Hg 171–172° C.

N,N' - [2 - (2' - phenyl-cyclohexen-3-carboxyl)-ethyl]-piperazine, obtainable by methods (b), (c): light yellow crystals, M.P. (Kofler) 145–147° C.

Tropyl - 2 - phenyl - cyclohexen-3-carboxylate methyl iodide, colourless crystals, M.P. (Kofler) 272–275° C.

While the invention has been described in particular with respect to the production of certain specific compounds and specific methods used in the production

thereof, it is apparent that variations and modifications can be made without departing from the spirit and scope of the invention.

What is claimed is:

5 1. A compound selected from the group consisting of compounds of the formula:

(I)

wherein R is selected from the group consisting of

and physiologically acceptable salts thereof.
